A. A. OLSEN

OIL WELL PUMP.

Filed Dec. 6, 1921

INVENTOR:
ALBERT A. OLSEN,
By Graham & Davis
ATTORNEYS.

UNITED STATES PATENT OFFICE.

ALBERT A. OLSEN, OF RANGER, TEXAS.

OIL-WELL PUMP.

Application filed December 6, 1921. Serial No. 520,255.

To all whom it may concern:

Be it known that I, ALBERT A. OLSEN, a citizen of the United States, residing at Ranger, in the county of Eastland and State of Texas, have invented a new and useful Improvement in Oil-Well Pumps, of which the following is a specification.

My invention relates to oil well pumps and more particularly to pumps which may be suspended at the bottom of a string of tubing in a well being operated through the ordinary type of pump or sucker rods.

The principal object of the invention is to provide a pump which will be adapted to pump oil containing sandy or gritty material and which may be operated intermittently in pumping oil containing said material without danger of the pump being clogged up by the sand, shale or other material settling out of the oil so pumped. In the ordinary production of oil, it is quite common to find associated with the oil large quantities of fine sand or silt, and it is a particular object of my invention to provide a pump which will operate satisfactorily under such conditions.

Such materials also have a highly abrasive action and tend to rapidly cut out the working surfaces of the pump. It is a further object of my invention to provide a pump in which these gritty or abrasive materials are almost wholly excluded from the working surfaces.

A still further object of my invention is to provide a pump which will be double acting so that a portion of the work is done on the downstroke, thereby equalizing the pull on the sucker rods and reducing the strains thereon.

Further objects and advantages will be made evident hereinafter.

Referring to the drawing which is for illustrative purposes only,

Fig. 1 is a vertical cross section through the upper portion of a pump equipped with my invention.

Fig. 2 is a section on a plane represented by the line 2—2 of Fig. 1.

Fig. 3 is a section on a plane represented by the line 3—3 of Fig. 1.

Fig. 4 is a vertical cross section of the lower part of the pump shown in Fig. 1.

In the form of the invention shown, I provide a collar 11 which is threaded at 12 for attachment to the tubing of the well, not shown, upon which the collar 12 is

screwed and upon which the stationary portion of the pump is suspended. Fastened in the lower end of the collar 12 is a nipple 13 which carries a second collar 14 at its lower end. Fastened in the collar 14 is a shell 15 carrying liners 16, the shell 15 and the liners 16 forming a working barrel in which a plunger 20 is reciprocated. The plunger 20 is ground to an accurate fit in the liners 16 and is secured to a member 21 having an opening 22 therethrough, the member 21 having a seat 23 upon which a valve 24 seats. The upper portion of the member 21 is secured in a member 25 having a central opening 26 therein, this opening 26 forming a cage in which the ball 24 is free to rise and fall. Threaded in fluid-tight relationship in the top of the member 25 is an eduction pipe 30 which extends up and is secured in a member 31 having an opening 32 therethrough. A seat 33 is secured in the top of the opening 32 and a valve 34 is free to seat thereon, this valve being carried in a cage 35 which is open at either side so that the central cavity 36 in which the ball 34 moves is in open communication with the space inside the tubing, not shown.

Seated in a conical seat 40 in the collar 11 is a plug 41 which carries packing 42 making a fluid-tight joint around the pipe 30. This packing 42 may be compressed by means of a nut 43. Secured on the bottom of the shell 15 is a collar 50 to which a nipple 51 is secured, this nipple carrying a collar 52. Seated on a tapered seat 53 in the collar 52 is a standing valve seat 54 having an opening 55 therethrough, this opening having a seat 56 and a standing valve ball 57. The ball 57 is carried in a cage 58 which is secured to a hollow garbutt rod 59. The garbutt rod 59 extends up inside the plunger 20 and is provided with a head 60 which engages a shoe 61 threaded in the bottom of the plunger in the event that the plunger is withdrawn from the liners 16.

The method of operation of the invention is as follows:

A line of sucker rods, not shown, extending downwardly through the tubing, not shown, is connected to the threaded end 70 of the member 33 and is used to lift the plunger 20 through the pipe 30 and its connected parts. On the up stroke of the plunger, the oil lifts the ball 57 and passes upwardly through the hollow garbutt rod 59 into the interior of the plunger 20. At the same

time, the balls 24 and 34 remain seated. As soon as the plunger reaches its upper position and starts downwardly, the ball 57 seats and the balls 24 and 34 are raised, oil 5 being forced upwardly through the pipe 30 into the space inside the tubing around the member 33. During this up and down motion, the hollow garbutt rod 59 remains in the position shown and is not disturbed except when it is desired to remove the working parts from the well. Due to the packing 42, oil is excluded from the space around the pipe 30 inside the liner 16. Any oil which is initially in this space on the first 10 upward stroke of the plunger is forced out due to the fact that the plug 41 will be raised from its seat and the oil expelled. As soon as the plunger starts on its downward motion, the plug 41 seats and a partial 15 vacuum is formed in the space around the pipe 30 inside the liner 16 and the nipple 13. While there may be some sand or silt in the oil in this space, this sand or silt is a relatively small amount and will not serve to 20 clog the pump or to greatly retard its action. This is due to the fact that the amount of oil is small and this small amount of oil which remains in this space is not changed on successive strokes of the pump. The 25 main flow of the oil is upwardly through eduction pipe 30 and while this oil may carry large quantities of sand and this sand may settle in the lower portion of the tubing when the pump is shut down, the method 30 of construction is such that this sediment has very little tendency to retard the operation 35 of the pump.

In the ordinary form of pump in which the sucker rods are connected directly to the 40 member 25 and in which the oil is forced from the opening 26 directly into the space inside the liner 16, it is evident that there is a great likelihood of a settlement of sand or silt on top of the member 25 and directly 45 against the wearing surfaces of the liner 16, especially when the pump is shut down. It is also evident with the sand or silt collected in this particular location that the first upward movement of the pump tends 50 to force this sand or silt down into the working surfaces between the plunger 20 and the liner 16 and that a rapid deterioration of these surfaces is to be expected.

In the event that it is desired to pull the 55 working portion of the pump from the well, the plug 41 will be lifted from its seat by the member 25 and the standing valve seat 54 and its connected parts will also be raised by means of the hollow garbutt rod 60 59 so that the plug 41, the pipe 30, the plunger 20, the hollow garbutt rod 59 and the standing valve seat 54 are all taken out of the well together.

It is also evident that at the same time 65 the balls 34, 24 and 57 with their seats are

also raised. In the practical working of my invention, I prefer to use both the ball 34 and the ball 24, but either of these balls may be dispensed with under certain conditions.

I claim as my invention:

1. A fluid pump for use with a well casing comprising a casing, a pump barrel, a plunger operating in the pump barrel, valve mechanism permitting the flow of the fluid in one direction, and means cooperating with the plunger to positively prevent contact of abrasives in the fluid pumped with any points of frictional engagement of the plunger and barrel. 70

2. A fluid pump for use with a well casing comprising a casing, a pump barrel, a plunger operating in the pump barrel, valve mechanism permitting the flow of the fluid in one direction, and means cooperating with the plunger to positively prevent contact 75 of the fluid pumped with the barrel. 80

3. A fluid pump for use with a well casing comprising a casing, a pump barrel, a plunger within the barrel, a stationary tube within the plunger through which the fluid passes, valve mechanism permitting the flow 90 of the fluid in one direction, and means on the plunger to prevent contact of the fluid pumped with the exterior of the plunger. 95

4. A fluid pump for use with a well casing comprising a casing, a pump barrel, a plunger within the barrel, a garbut-rod within the plunger through which the fluid passes, valve mechanism permitting the flow of fluid in one direction, and a shoe on the plunger to prevent contact of the fluid pumped with the exterior of the plunger. 100

5. A fluid pump for use with a well casing comprising a casing, a pump barrel, a plunger within the barrel, a stationary tube within the plunger through which the fluid passes, valve mechanism permitting the flow of the fluid in one direction, means on the plunger for preventing contact of the fluid pumped with the exterior of the plunger, a 105 plug in the casing unseated with upward pressure, and means for operating the plunger reciprocating in the plug. 110

6. A fluid pump for use with a well casing comprising a casing, a pump barrel, a plunger within the barrel, a hollow garbut-rod within the plunger through which the fluid passes, valve mechanism permitting the flow of fluid in one direction, a plug in the casing unseated with upward pressure, means for operating the plunger reciprocating in the plug, and a shoe on the plunger to prevent contact of the fluid pumped with the exterior of the plunger. 115

7. A fluid pump for use with a well casing comprising a casing, a pump barrel, a plunger within the barrel, a stationary tube within the plunger through which the fluid passes, a one-way valve in the stationary tube, valve mechanism preventing down- 120 125 130

ward flow of liquid in the plunger, and means on the plunger to prevent contact of the fluid pumped with the exterior of the plunger.

5 8. A fluid pump for use with a well casing comprising a casing, a pump barrel, a plunger within the barrel, a hollow garbut-rod within the plunger through which the fluid passes, a one-way valve in the garbut-
10 rod, a one-way valve in the plunger located above and relatively near to the upper end of the garbut-rod, another one-way valve located before the last mentioned valve, a head for the garbut-rod, and a shoe on the plunger
15 to prevent contact of the fluid pumped with the exterior of the plunger and to cooperate with said head in removing the device from a well.

9. A fluid pump for use with a well casing comprising a casing, a pump barrel, a plunger operating in the pump barrel, a plug in the casing unseating with upward pressure, means for operating the plunger reciprocating in the plug, valve mechanism
20 permitting the flow of the fluid in one direction, and means cooperating with the plunger to positively prevent contact of abrasive in the fluid pumped with any points of frictional engagement of the barrel and
25 plunger.

10. A fluid pump for use with a well casing comprising a casing, a pump barrel, a plunger within the barrel, a stationary tube within the plunger through which the fluid
30 passes, a plug in the casing unseatable with

excessive upward pressure, means for operating the plunger reciprocating in the plug, a one-way valve in the plunger.

11. A fluid pump for use with a well casing comprising a casing, a pump barrel, a plunger within the barrel, a plug in the casing unseating with upward pressure, means for operating the plunger reciprocating in the plug, a hollow garbut-rod within the plunger through which the fluid passes, a one-way valve in the garbut-rod, a one-way valve in the plunger located above and relatively near to the upper end of the garbut-rod, another one-way valve located above
40 the last mentioned valve, a head for the garbut-rod, and a shoe on the plunger to prevent contact of the fluid pumped with the exterior of the plunger and to cooperate with
45 said head in removing the device from a well.

12. A fluid pump for use with a well casing comprising a casing, a pump barrel, a plunger within the barrel, a stationary tube within the plunger through which the fluid passes, a plug in the casing unseatable with
50 excessive upward pressure, means for operating the plunger reciprocating in the plug, and means for preventing discharge of the fluid through the pump in a downward direction.

In testimony whereof I have hereunto set my hand at Ranger, Texas, this 25th day of November, 1921.

ALBERT A. OLSEN.
